(57) **CLAIM**

The ornamental design for cab molding with a display and controls, as shown and described.

DESCRIPTION

FIG. 1 is a front, right-side, and top view of cab molding with a display and controls, showing one embodiment of the new design.

FIG. 2 is a front elevation view of the cab molding with a display and controls.

FIG. 3 is a top plan view.

FIG. 4 is a rear elevation view.

FIG. 5 is a right-side elevation view.

FIG. 6 is a left-side elevation view.

FIG. 7 is a front, right-side, and top view.

FIG. 8 is a rear, right-side, and top view; and,

FIG. 9 is a second rear, right-side, and top view.

The broken lines represent elements of the cab molding with a display and controls that are not seen when the product is installed, which form no part of the claimed design.
